UNITED STATES PATENT OFFICE.

EDWARD F. SCHWORM, OF BEACH CITY, OHIO.

ROTARY TOOTHRUSH.

1,420,388.

Specification of Letters Patent. Patented June 20, 1922.

Application filed June 11, 1921. Serial No. 476,913.

To all whom it may concern:

Be it known that I, EDWARD F. SCHWORM, a citizen of the United States, residing at Beach City, in the county of Stark and 5 State of Ohio, have invented certain new and useful Improvements in Rotary Tooth-brushes, of which the following is a specification, reference being had to the accompanying drawings.

10 The present invention has for its purpose the provision of a brush of this character, whereby through revoluble movement, the bristles of the brush may pass through the transverse crevices of the teeth and between 15 the teeth, as well as upon the surfaces, in order to thoroughly clean the teeth.

Another purpose is the provision of improved means for supporting the handle of the brush, and coupling it to a revoluble 20 flexible shaft, which may be revolved or rotated in any suitable manner, preferably electrically.

Still another purpose consists in a suitable 25 casing including a pliable tube or casing for the flexible shaft, there being a socket carried by one end of the flexible shaft and located within the casing, so that the handle of the revoluble brush may be easily and quickly attached and detached to the flexible 30 shaft, and at the same time revolve with the shaft, the bristles of the brush extending radially from the brush shaft, so as to work between the teeth, and into the transverse crevices and cavities.

35 A further purpose embodies the provision of a shield to be attached and detached to and from the casing, and adapted when attached to the casing to shield one-half of the brush, whereby the smooth part of the 40 shield may contact with the inner surface of the cheek of the user.

When cleaning the portions of the teeth adjacent the inner portion of the mouth, the shield may be removed, but when cleaning 45 the sides of the teeth toward the cheek, the shield may be attached, so as to prevent the bristles of the brush from sweeping against the inner surface of the cheek.

A still further purpose is the provision 50 of means for steadyng the brush shaft and preventing the same from vibrating, during the rotation of the brush, either when the shield is applied, or when the shield is detached, and a plug or bushing used instead 55 thereof.

While the design and construction at

present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features 65 and combination of parts, as will be herein-after set forth, shown in the drawings and claimed.

In the drawings:

Figure 1 is a view in elevation, showing 70 the revoluble tooth brush constructed in accordance with the invention.

Figure 2 is a longitudinal sectional view through the same.

Figure 3 is a view of the tooth brush, 75 showing parts of the casing in section and parts in elevation, with the shield removed.

Figure 4 is an enlarged detail sectional view through the connection between the casing and the pliable tube, and between the 80 brush shaft and the flexible shaft.

Figure 5 is a cross sectional view on line 5—5 of Figure 4.

Referring to the drawings, 1 designates a pliable tube constructed of any suitable pliable material such as rubberized fabric or the like, and which is provided with a metal extension sleeve 2, which is connected to a tubular casing 3 having a handle 4. A flexible shaft 5 is located in the pliable tube 1 90 and may be connected to any suitable source of power (not shown), whereby the shaft may be rotated.

In the average homes of recent years, and those to be constructed, electricity is used 95 for lighting, heating, cooking, cleaning and performing all the necessary work, hence small electric motors may be used in connection with the source of current, such motors as those used in vibrators, so that the present form of revoluble tooth brush may be easily and quickly attached and detached. In other words the flexible shaft may be coupled to such motors, so that any form of revolving instrument may be attached and 105 detached to the flexible shaft. It is obvious that not only tooth brushes may be used in connection with the flexible shaft, but other brushes, such as brushes for cleaning bottles, jars, glasses and the like.

110 However the flexible shaft 5 terminates in a socket 7, which is rectangular in cross

section, and arranged transversely of the socket at diametrically opposite points are springs 8. These wire springs are fastened in openings formed in the wall of the socket, 5 and are engaged with an annular groove 9 in one end of the tooth brush shaft 10. In other words the tooth brush shaft 10 has an extension 11 rectangular in cross section to engage the socket of the shaft 5, and the ext- 10 remity of the rectangular extension has a frusto-conical head 12, between which and the rectangular extension 11 the annular groove 9 is formed. When attaching the brush on the shaft 10, the rectangular ex- 15 tension 11 is forced into the socket, until the frusto-conical head engages between the two springs, separating them sufficiently to permit the springs to engage the annular groove 9, thereby preventing the brush shaft from 20 detaching in an axial direction. In other words preventing the brush shaft from pulling out of the socket. The handle 4 of the casing 3 may be constructed of any suitable fibre, or hard rubber, wood or the like, or 25 any other suitable material, and is applied to the casing 3 in any suitable manner.

The end portion 13 of the casing has interior threads 14, with which the threads 15 of a bushing, or the threads 16 of one end 30 of the shield engage. The bearing bushing 17 is first attached to the casing, and the brush shaft is passed through the same, until the frusto-conical head 12 positions beyond the springs of the socket, in which case 35 the brush shaft will rotate with the flexible shaft 5. This bushing 17 has an interior annular recess 18, which receives a suitable packing or the like 19, thereby not only preventing vibrations of the brush shaft, 40 but also permitting the shaft to rotate easily, and without frictional wear on the metal parts.

The shield 20 is also provided with an annular recess 21 to receive a packing 22 to 45 prevent vibration of the brush shaft. This shield terminates in a semi-circular portion 23, which houses or shields one-half of the brush 24. One end of the brush shaft has a socket 25, which receives the stud 26 on one 50 end of the semi-circular housing of the shield, thereby holding the brush steady. It will be noted that the shield 20 remains stationary with the casing 3, and since the flexible shaft is adapted to rotate, the brush

shaft correspondingly rotates. By means of 55 the shield covering one-half of the brush, the bristles of the brush are prevented from sweeping against the inner surface of the cheek of the user. Furthermore the shield prevents the water or other cleaning sub- 60 stance being thrown centrifugally from the bristles of the brush during its revoluble movements, particularly when cleaning the faces of the teeth facing inwardly of the mouth.

When the shield is used, the bushing is de- 65 tached, and the shield connected in place. This is accomplished by removing the bushing, then attaching the shield to the shaft of the brush, after which the brush shaft is in- 70 serted into the casing 3, so that the exten- 75 sion 11 may engage the socket, then the shield is connected to the casing 3.

It is obvious that each home may have 80 electrical means for operating the flexible shaft, consequently the brushes belonging to the respective members of the household may be attached and detached, as they are used by their owners. In other words each home may be equipped with a flexible shaft, the casing and the socket, then each member of the household may have a brush shaft, inser- 85 tible in the socket of said casing. Obviously each member of the household may clean his or her teeth with a revolving brush.

The invention having been set forth, what is claimed as being useful is:

In a device of the character described, a handle having a longitudinal bore there- 90 through, a cap detachably engaged upon one end of the handle and formed with a hole of less diameter than the bore of the handle, a drive shaft journaled through said hole in the cap and formed with an enlarged portion 95 rotatable within the bore of the handle and formed with a rectangular socket, a spindle rotatable within the bore of the handle and having one end formed with a rectangular extension fitting within said socket and termin- 100 ating in a head and a constricted neck, and a pair of spring wires extending trans- versely of the socket and engaging within said constricted neck for holding the spindle against longitudinal displacement relatively to the socket.

In testimony whereof I hereunto affix my signature.

EDWARD F. SCHWORM.
